UNITED STATES PATENT OFFICE.

JOSEPH E. VILLATORE, AND BERNARD MAMMONE, OF NEW YORK, N. Y.

HEADREST SUPPORT.

Application filed January 6, 1928. Serial No. 244,803.

Our present invention relates generally to supporting devices, and has particular reference to a device for employment with barber chairs or the like for supporting a head rest during non-usage thereof.

It is well known that barber chairs of modern character are provided with head rests which are removable with respect thereto. It is an object of our present invention to provide a head rest support which may be removably associated with the chair itself for accommodating a head rest when the latter is removed from the chair.

A chair of the character referred to is generally provided with a depending flange peripherally arranged with respect to the seat. This flange generally conforms in appearance to that of the rest of the chair; or in other words, where the chair is provided with a coating of white enamel or the like, the exposed portion of this flange is similarly coated so that the appearance of the entire chair is rendered attractive.

Our invention has particular reference to chairs of the last mentioned character, and it is an object to provide a head rest support which may be removably attached to said flange in an efficient and satisfactory manner.

More particularly, it is an object to provide a device which will not impair the coating of enamel; which may therefore be attached and removed at will without marring the appearance of the chair; which is particularly adapted for firm association with a flange of the character mentioned; which is provided with means for rendering said attachment especially firm and secure; which is so constructed as to provide a highly efficient support for the head rest; which is so constructed that when the head rest is associated therewith or removed therefrom there is no danger of marring the surface of the chair by the head rest itself; which presents an attractive and unobtrusive appearance when it is attached; and which is of extremely simple construction, rendering the manufacture thereof most inexpensive.

One feature of our invention lies in providing a support of a single integral blank of material, preferably nickelized metal or the like.

Another feature lies in providing protective coatings such as felt along predetermined surfaces to protect the surfacing of the chair.

Another feature lies in constructing the integral blank in such a manner as to provide not only an extremely efficient attaching portion, but also an extremely attractive and efficient main or supporting portion.

Briefly, our device comprises an integral blank which is cut and shaped to provide two U-shaped arms constituting the attaching portion, and an angularly constructed main portion for receiving and accommodating the head rest. The U-shaped arms or straps are adapted to assure firm attachment of the device, and in a preferred form of our invention a pair of thumb screws are associated with the straps to permit clamping thereof around the chair flange.

For the attainment of the foregoing objects and such other objects as may hereinafter appear or be pointed out, we have constructed a device embodying the features of our invention and illustrated in the accompanying drawings, in which—

Figure 1 is an elevational view of a support constructed in accordance with the present invention and associated with a chair of the character mentioned, a portion of the chair flange being broken away;

Figure 2 is a plan view of the cut blank which may be employed to provide the device;

Figure 3 is a cross-sectional view taken along the line 3—3 of Figure 2; and

Figure 4 is a perspective view of our complete device ready for attachment to a chair.

In Figure 1 we have shown a portion of a barber's chair wherein 10 represents the usual axial pedestal, and 11 is illustrative of the usual flange which depends peripherally from the seat of the chair. In well constructed chairs of modern character, the flange is rounded at its lower edge, and is coated with enamel or the like. 12 represents the rear portion of the cushioned seat, and 13 a portion of the arm rest support.

A chair of the character typified is usually provided with a removable head rest which is shown in dot and dash lines in Figure 1, this head rest comprising a main portion 14 of padded construction, and a shank 15 provided with teeth or otherwise suitably constructed to permit adjustment and removability thereof from the top of the back of the chair. The main portion 14 is usually set at a slight angle to the shank 15, and for this reason the upper portion 16 of the shank may be disposed at an angle to the main portion there-

of so as to support the portion 14 at the proper angle with respect to the shank 15.

In Figure 4 we have shown a head rest support constructed in accordance with our invention. It comprises a main portion 17 and an attaching portion 18. The latter comprises two spaced U-shaped straps, the arms of which are respectively aligned. More particularly, the inner arm 19 of one strap is aligned with the inner arm 19' of the other, while the outer arm 20 of the one strap is aligned with the outer strap 20' of the other. Each strap has a curved medial portion 21 substantially semi-circular in cross-section.

The main portion 17 extends laterally from the upper ends of the arms 20 and 20', and it comprises two parts; the downwardly directed part 22 which is provided with an aperture 23, and the end part 24 which is in the nature of a lip horizontally disposed for a purpose presently to be described. It will be noted that the parts 22 and 24 define an upwardly opening V as shown more clearly in Figure 1.

The inner surfaces of the arms 20 and 20' are preferably provided with layers of felt 25 or the like; and the free ends of the straps are provided with tapped openings to accommodate the thumb screws 26. It will be noted that the axes of the screws 26 are substantially perpendicular to the planes of the arms.

In Figures 2 and 3 we have shown an integral blank from which our support may be formed by the simple procedures of cutting, stamping, and shaping. The blank employed is elongated in character and is provided not only with the aperture 23 but also with a longitudinal slot 27 extending almost to the aperture 23 and defining the straps which are ultimately shaped to provide the U-shaped attaching straps. The dotted lines in Figure 2 indicate the lines along which the blank is folded or bent, and the portions 24, 22, 20, 20', 21, 19, and 19' are easily discernible. In Figures 2 and 3, the tapped openings 23 for the accommodation ultimately of the screws 26 are clearly shown.

The method of employing our device will be obvious from the description given. Upon reference to Figure 1, it will be noted that the U-shaped straps are applied over a selected portion of the flange 11, and when the proper position is reached, the thumb screws 26 are manipulated to clamp the straps and the entire device to the selected portion of the flange. It is to be noted that the curved portions 21 of the straps afford the possibility of a snug fit thereof around the flange 11. It is to be noted also that the layers of felt 25 prevent injury to the enameled outer surface of the flange 11. It is to be noted further that the screws 26 are disposed beneath the seat of the chair and hence are out of visible position.

The main portion 17 disposes itself as

shown in Figure 1, with the angular part 22 extending downwardly and away from the chair. When the head rest is applied, the shank 15 is passed through the aperture 23 until the main portion 14 of the head rest is received and accommodates itself upon the main portion of the supporting device. The angularity of the part 22 causes the device to function efficiently in connection with the angularly positioned head rest 14, and the end or lip part 24 enhances the firmness and satisfactory character of the support afforded to the head rest.

The provision of the two spaced U-shaped straps serves not only to lighten the entire supporting device, but it serves also the extremely valuable function of affording a proper accommodation of the device to the curved flange 11. If only one relatively narrow strip were to be provided, the device would not be sufficiently retained in immovable position. On the other hand, if a relatively wide U-shaped strap were provided, the snug accommodation to the curved flange 11 would not be possible. In accordance with the present structure, the device may be firmly and securely engaged around the flange 11 at any desired point, and when the screws 26 have been manipulated, it is held in firm and highly efficient security. At the same time, it is to be noted that the attachment is removable, and that upon removal the outer surface of the flange 11 will still retain its original attractive and unmarred appearance.

It will be obvious that changes in the details herein described and illustrated for the purpose of explaining the nature of our invention may be made by those skilled in the art without departing from the spirit and scope of the invention as expressed in the appended claims. It is therefore intended that these details be interpreted as illustrative, and not in a limiting sense.

Having thus described our invention and illustrated its use, what we claim as new and desire to secure by Letters Patent is—

1. For use with a chair having a seat and a depending peripheral flange, a head rest support comprising a main supporting portion and a bifurcated attaching portion, the latter comprising two spaced U-shaped straps whose arms are respectively aligned, whereby said straps may be engaged about spaced portions of said flange, and said main portion comprising two angularly disposed parts defining an upwardly opening V within which the head rest is adapted to be accommodated.

2. For use with a chair having a depending flange, a head rest support comprising an integral metallic blank cut and shaped to provide a main supporting portion and an attaching portion, the latter comprising two spaced U-shaped straps engageable about spaced portions of said flange, and the main portion comprising two angularly disposed

parts, the part adjacent to the straps extending downwardly at an angle, and the end part extending substantially horizontally.

3. For use with a chair having a depending flange, a head rest support comprising an integral elongated metallic blank cut and shaped to provide a main portion and an attaching portion, the main portion comprising two parts defining an upwardly opening **V**, and the attaching portion comprising two spaced upwardly opening **U**-shaped straps, the arms of the **U**'s being respectively aligned, whereby the straps may be engaged upwardly around said flange, and whereby a head rest may be accommodated upon the main portion and within the **V** defined thereby.

4. A barber chair headrest support formed from an elongated metallic blank formed

from sheet metal, which blank has adjacent one end an opening sufficiently large to receive therethrough the depending portion of a barber chair headrest and is slotted for a major portion of its length, said support having the slotted portion **U**-shaped to form the attaching portion for the support and having the intermediate apertured portion angularly positioned with reference thereto, the opposite end portion being bent at an angle to the said intermediate portion and substantially at right angles to the general direction of the opposite **U**-shaped end portion.

In witness whereof we have signed this specification this 5th day of January, 1928.

JOSEPH E. VILLATORE.
BERNARD MAMMONE.
